CLAIM

The ornamental design for an electronic muscle stimulator low frequency pulse waist belt, as shown and described.

DESCRIPTION

FIG. 1 is a perspective view of an electronic muscle stimulator low frequency pulse waist belt according to the present invention;

FIG. 2 is a front view of the electronic muscle stimulator low frequency pulse waist belt of FIG. 1;

FIG. 3 is a rear view of the electronic muscle stimulator low frequency pulse waist belt of FIG. 1;

FIG. 4 is a left side view of the electronic muscle stimulator low frequency pulse waist belt of FIG. 1;

FIG. 5 is a right side view of the electronic muscle stimulator low frequency pulse waist belt of FIG. 1;

FIG. 6 is a top plan view of the electronic muscle stimulator low frequency pulse waist belt of FIG. 1; and,

FIG. 7 is a bottom plan view of the electronic muscle stimulator low frequency pulse waist belt of FIG. 1.
